Patented Jan. 20, 1914.

UNITED STATES PATENT OFFICE.

JASON C. STEARNS, OF WORCESTER, MASSACHUSETTS.

LAMP-REFLECTOR.

1,084,713.

Specification of Letters Patent.

Patented Jan. 20, 1914.

Application filed December 23, 1912. Serial No. 738,153.

To all whom it may concern:

Be it known that I, JASON C. STEARNS, a citizen of the United States, residing at Worcester, in the county of Worcester and 5 State of Massachusetts, have invented a new and useful Lamp-Reflector, of which the following is a specification.

This invention relates to a reflector for electric lamps, particularly those in common 10 use on motor vehicles and the like.

The principal objects of this invention are to provide a construction in which the electric lamp can be removed very conveniently and readily for replacement and repairs 15 without interfering with or even opening, the front glass, and without providing a bulky and expensive connection at the rear, and also without reducing the reflecting surface; in other words, without making the 20 reflecting surface smaller than it is on those reflectors which are so arranged that the lamp has to be removed from the front.

The invention also involves a construction and arrangement of parts so that when the 25 lamp is removed from the back it will be capable of being entirely taken out of the reflector and moved around and manipulated at ease.

Further objects and advantages of the invention will appear hereinafter.

Reference is to be had to the accompanying drawings in which,

Figure 1 is a central longitudinal sectional view of an automobile lamp and reflector 35 constructed in accordance with this invention; Fig. 2 is a side view of the removable section of the reflector with the lamp attached and showing the relation of the same to the end of the outer part of the reflector, 40 and Fig. 3 is an end view of the removable section and lamp.

The invention is shown as applied to an ordinary lamp casing 10 having the usual connections 11 for the electric wires and the 45 usual front glass 12. In this case the glass can be permanently secured in position if desired, which is one of the advantages of the invention. The reflector is shown as comprising an outer stationary section 13 and 50 an inner removable concave section 14. The outer section is provided with a perforation for receiving the inner section 14 and is provided with an inwardly extending flange 16 and an outwardly extending cylindrical 55 guide 17 having bayonet joint slots 18 there-

on. The inner section 14 is also provided with an outwardly extending cylindrical guide 20 fitting in the guide 17 and at its inner edges it is provided with a circumferential notch 21 for receiving the circular 60 projection 16. This notch and projection are of the same thickness so that the inner surface on the reflector section 14 constitutes an accurate continuation of the inner surface of the outer section 13 and together 65 the two sections constitute in this case a parabolic reflector. The inner section is also provided with a screw-threaded projection 23 at the center extending outwardly therefrom for receiving any desired kind of connections 24 from the electrical wires, said connections also having a socket for supporting an incandescent lamp 25. The section 14 and the perforation through which it passes are sufficiently large so that the lamp 75 will pass through the perforation and can be drawn out from the main reflector section through the back. On the flange 20 are a series of pins 26 having heads adapted to enter the bayonet joint slots 18 and in place 80 of one of them is a headed screw 27 for fastening the removable section in position on the stationary outer section.

The inner section preferably is concentric with the outer section so that the lamp is 85 moved out and in axially.

It will be seen that the outer casing 10 can be dispensed with if desired and that the glass 12 can be sealed permanently in place with this invention.

The other features of construction are not described in detail as any desired means can be employed for holding the front section in position and connecting up the parts, but there are flexible electrical connections 28 95 between the two members 11 and 24 so that when the section 14 is taken out with the lamp it can be manipulated as desired so as to be inspected or repaired and the lamp replaced. In this way the entire interior of 100 the reflector and support for the lamp are utilized for reflecting purposes and the lamp is manipulated in a most convenient manner without necessitating the removal of the glass or the opening of the front of the 105 lamp, and in fact the reflector can be cleaned from the back if desired.

Although I have illustrated and described only a single embodiment of the invention, I am aware of the fact that modifications 110

can be made therein by any person skilled in the art without departing from the scope thereof as expressed in the claims. Therefore, I do not wish to be limited to all the 5 details of construction herein shown and described, but

What I do claim is:—

1. As an article of manufacture a reflector presenting a continuous concave reflecting surface and an electric light detachably mounted in front of and within said concave surface, the central portion of said reflector being removably secured to the outer portion to permit insertion of the light 10 from the rear.
2. As an article of manufacture, a reflector comprising two concave sections removably connected with each other, one inside the other, the reflecting surface of the inner 15 section constituting a continuation of the reflecting surface of the outer section and having means thereon for detachably supporting a lamp, the outer section having a guide 20 on the rear surface thereof for the inner section, and means on the inner section coöper- 25

ating with the guide and securing the sections together.

3. A reflecting lamp comprising an outer casing, a concave reflector secured therein and having an opening through its central portion, a cylindrical flange secured in the rear side of said reflector and slightly larger in diameter than said opening, a cylindrical sleeve fitting within said flange and having secured to its forward end a second concave reflector adapted to constitute a continuation of the main reflecting surface, a bayonet lock for drawing the inner surface firmly against the reflector, and means for securing the same in position, said inner section being provided with means for detachably securing an electric light thereto.

In testimony whereof I have hereunto set my hand, in the presence of two subscribing witnesses.

JASON C. STEARNS.
